UNITED STATES PATENT OFFICE.

WILLIAM A. BARRY, OF LITTLE ROCK, ARKANSAS.

SAFETY-RAZOR.

1,351,713.

Specification of Letters Patent. Patented Aug. 31, 1920.

Application filed June 12, 1920. Serial No. 388,594.

To all whom it may concern:

Be it known that I, WILLIAM A. BARRY, a citizen of the United States, residing at Little Rock, in the county of Pulaski and State of Arkansas, have invented certain new and useful Improvements in Safety-Razors, of which the following is a specification.

This invention relates to razors and more particularly to that type commonly known as safety razors.

An object of the invention is to provide a suitable safety razor which will readily receive several different types of blades, and which will be efficient in use with any one of said types of blades.

A further object is to provide a safety razor which will adjust the cutting edges of the blades, by bending or contracting or expanding the back or guard plate as desired.

A still further object of the invention is to provide a suitable handle portion, which will permit of a multiplicity of adjustments of angle for shaving, and which may be detached from the razor proper, or knocked down for cleaning and packing.

Other objects will appear as the description proceeds.

50 In the accompanying drawings which form a part of my specification,—

Figure 1 is a side elevation of the safety razor;

Fig. 2 is an end elevation thereof;

55 Fig. 3 is a perspective view of the front plate with ears and pin slots;

Fig. 4 is a perspective view of the front plate without ears, but with positioning pins;

40 Fig. 5 is a perspective view of the guard with pin slots;

Fig. 6 is a perspective view of the guard with pins or studs;

45 Fig. 7 is a perspective view of the preferred type of adapter;

Fig. 8 is a modification of the adapter, for use with the front plate shown in Fig. 4;

Fig. 9 is a perspective view of one of the blades;

50 Fig. 10 is a side elevation of the handle with threaded stud or end member;

Fig. 11 is a side elevation of the handle, partly in section, with an internally threaded socket or end member;

55 Fig. 12 is a section view taken on the line 12—12 of Fig. 11;

Fig. 13 is a perspective view of the front plate with ears;

Fig. 14 is a plan view of the guard plate;

Fig. 15 is a perspective view of the front 60 plate with ears, and with the adapter in position;

Fig. 16 is an end elevation of the guard plate, with blades superimposed thereon;

Fig. 17 is a plan view of the razor assem- 65 bled.

Like reference numerals refer to like parts throughout the following specification.

The handle member 1 of the safety razor 70 is provided with a split socket 2, the outer end of which is threaded as at 3, and receives an adjusting nut 4. A threaded stud 5 or internally threaded socket member 6 is provided at its end with a ball or journal 75 7, which seats in and cooperates with the split socket 2. With this structure, it will be seen that a multiplicity of angles may be had for the handle.

A front plate 8 is provided with the ears 80 at its opposite ends, and has a longitudinal slot 10 therein, located in alignment with and between said ears. A threaded stud 11 is provided midway of said plate 8, and at right angles thereto. Bearing surfaces 12 85 extend on opposite sides of the slot 10, throughout the entire length of the plate 8, and are provided with a plurality of slots or openings 13, later to be described.

An adapter 14 is provided with a central 90 opening 15, and a pair of lugs or pins 16 disposed midway between said central opening and the ends of the adapter.

The flexible guard plate 17 is provided with cut-away slots 18 at its ends, and with 95 a central opening 18' and a pair of openings 19 disposed midway between said central opening and the ends of the guard. A plurality of pins 20 are positioned at points adjacent the serrated edges 21 of the guard 100 plate 17. The blade 22 is provided with oppositely disposed cutting edges, and may or may not be flexible. Openings 23 are provided in said blade for purposes of packing, and also for fitting over the pins 20. It will 105 be seen that when the adapter 14 is placed in the slot 10 in the front plate 8, and the blades 22 placed on the guard plate 17, so that the pins 20 engage and fit in the openings 23, the guard plate may be placed onto 110 and in contact with the front plate, so that the lugs 16 on the adapter will enter the

openings 19, and the pins 20 will enter the slots 13. Consequently upon placing the handle on the threaded stud 11, the blades will move inward and outward with relation to the front plate, as the handle is tightened or loosened. The guard plate 17 is slightly bowed at its central portion to effect the moving of the blades upon the operation of the handle.

- 10 The front plate 24 is provided with a curved channel in its inner face and a central opening 25, and has a plurality of studs or pins 26 disposed midway between the central opening and the ends of the plate.
- 15 At either side of said plate is a flattened bearing surface 27, which extends the entire length of the plate, and receives a plurality of pins 28. Cut-away slots 29 are made in the opposite ends of the front plate 24, and
- 20 a longitudinally extending channel or slot 30 is provided in the outer surface of said plate.

An adapter 31 is provided with a threaded stud or shank 32, and has its ends bent up at right angles to form the ears 33.

The guard plate 34 is exactly similar to the guard plate 17, except that there are a plurality of slots 35 adjacent the serrated edges 36, in place of the pins 20. Said plate 30 34 is formed of a rigid material, and will not bend. In assembling this structure, the adapter 31 is placed in the slot 30 in the outer face of the front plate 24, so that the stud or shank 32 extends upward through 35 the central opening 25. The blades 22 are then placed on the pins 28, and the guard plate 34 superimposed thereon. It will be seen that the front plate in this instance is flexible or springy, due to the longitudinal 40 slot being positioned and formed as it is. The handle member 1 is placed on the stud or shank 32 and tightened down. Upon tightening the handle, the blades and front plate will be moved outward, while upon 45 loosening, the handle will draw the blades in more to the center.

In my preferred form, the front plate 35 is made rigid, and is provided with integrally formed ears 36, and an integrally 50 formed threaded stud 37. In the inner face of the front plate 35, is formed a longitudinally extending slot 38, for the reception of the adapter 14, illustrated in Fig. 7 of the drawings.

55 The blade or blades 22 are slightly longer than the front plate 35, and are similar to blade shown in Fig. 9 of the drawings.

The guard or back plate 39 is formed of resilient or springy metal, which is made 60 more thin at the inner portion 40, and bowed to effectively cause the serrated side members 41 to advance or retract as the handle member 1 is tightened or loosened, thereby permitting a number of adjustments for 65 shaving.

It will be seen that the blades 22 engage the ears 36, but are separated from the stud 37 by a slight margin or distance. Thus it is seen that the ears form the stopping or limiting means for the blades.

The assembly and operation of my improved or preferred type of razor is as follows: The blades are placed on the front plate in engagement with the ears 36, after which the guard or back plate is superimposed thereon, and the handle member placed in position and tightened down until the desired cutting edge is had. It will be seen that when the blades are in position on the guard member or plate, and the front plate is in position, the edges of the front plate are outward and beyond the line of center of the blades, thereby holding them from movement. As before mentioned, when the handle is tightened, the guard advances, due to the resiliency of the portion 40, and retracts when the handle is loosened.

If it is desired to use another type of blade, the adapter 14 is placed in the slot 38, after which the desired blade is placed in 90 position on the adapter, and the guard plate superimposed thereon. The handle member, when in position will cause the same advancing and retracting of the guard.

The adapter may be readily removed from 95 the front plate for cleaning, and will only be used when desired to use a single larger blade.

It is not thought that the idea of using a double edge blade is new, but the particular 100 structure and arrangement of the hereinbefore described parts is thought to be novel.

It will be understood that either type of handle illustrated in the drawing may be just as successfully used. Also, that either 105 type of front and guard plate may be used and one part substituted for the other.

I do not limit myself to the specific arrangement and construction of parts, as it is known that many minor changes in detail of construction may be resorted to without departure from the spirit of the invention.

This application is a continuation in part of my former application for safety razors, 115 Serial No. 382,671, filed May 19, 1920.

Having thus described my invention what I claim as new and desire to secure by Letters Patent of the United States is:

1. In a safety razor, a blade, superimposed members between which the blade is held, one of said members having means for positively fixing the position of the blade with reference thereto, and means for flexing the one member to slide the blade along 125 the other member to vary the position of the edge of the blade with reference to said other member.

2. In a safety razor, a blade, members between which the blade is held, the first mem- 130

ber having means for holding the blade in fixed position with reference thereto, and a handle holding the members together and operable to flex the one to slide the blade 5 along the other to advance or retract the edge of the blade with reference to the edge of said other member.

3. In a safety razor, a blade, members between which the blade is held, the one member having means for holding the blade in fixed position with reference thereto, and a common means for holding the members together and for flexing the one to slide the blade along the other to advance or retract 15 the edge of the blade with reference to the edge of said other member.

4. In a safety razor, a blade, plates between which the blade is held, means for holding the blade in fixed position relative to one plate, the said plates being of arcuate conformation in cross section and opposed in relative position, and a common means for holding the said plates together and flexing the one to slide the blade along the other 25 to advance or retract the edge of the blade with reference to the edge of said other member.

5. In a safety razor, a front plate formed with seats adjacent its longitudinal edges, 30 razor blades resting upon said seats, a guard formed with seats resting against the opposite sides of the blades, means for holding the blades in fixed position relative to the front plate, and a handle engageable with the front plate and with the guard, whereby 35 the front plate may be flexed to slide the blade along the guard to advance or withdraw the edges of the blades with reference to the edges of the guard.

40 6. In a safety razor, a front plate of arcuate conformation in cross section and formed with seats adjacent its longitudinal edges, the said plate being reduced in thickness at the peak of the arch, blades resting upon 45 said seats, the seats having means to preclude angular movement of the blades, a guard resting against said blades on those sides opposite the seats, and adjustable means interconnecting the plate and guard 50 whereby the former may be flexed to vary the positions of the edges of the blades with reference to the edges of the guard.

7. In a safety razor, a front plate of arcuate conformation in cross section and formed 55 with seats adjacent its longitudinal edges, the said plate being reduced in thickness at the peak of the arch, blades resting upon said seats, the seats having means to preclude angular movement of the blades, a 60 guard resting upon said blades on those sides opposite the seats, and a handle attachable to the plate and engaging with the guard, the handle being attachable angularly so that its being turned may cause the plate 65 to be flexed to vary the positions of the edges

of the blades with respect to the edges of the guard.

8. In a safety razor, a front plate of arcuate conformation in cross section, the plate being reduced in thickness at the peak of 70 the arch and being formed with seats adjacent its longitudinal edges, studs upstanding from the seats, a central stud upstanding from the concave face of the plate, blades carried upon the seats and formed with 75 holes engaging the studs thereon, a guard formed with holes through which the said center stud and the guide studs loosely pass, the guard resting upon the blades, and a handle formed with a socket engageable with 80 the central stud, the handle bearing upon the guard and being adjustable along said stud so that the said plate may be flexed for the useful purpose herein specified.

9. In a safety razor, a blade, superimposed members between which the blade is held, one of said members having a reduced central portion, means for positively positioning the blade with reference thereto, and means for flexing the one member to slide 90 the blade along the other member to vary the position of the edge of the blade with reference to said other member.

10. In a safety razor, a clamping member having a reduced central portion and enlarged bearing surfaces at opposite sides thereof and lying substantially in the same plane.

11. In a safety razor, a clamping member having a flexible central portion and enlarged bearing surfaces at opposite sides thereof and lying substantially in the same plane.

12. In a safety razor, a blade, a clamping member having a reduced central portion 105 and enlarged bearing surfaces on opposite sides thereof, and blade engaging means on said bearing surfaces.

13. In a safety razor, a blade, a curved clamping member having plane surfaces at 110 opposite sides thereof, and lying in substantially the same plane.

14. A safety razor head or mount, an adjustable handle thereon, the parts of the handle being enlarged and projecting laterally adjacent their connected ends, thereby producing a limited adjustment.

15. A safety razor comprising a front plate, a guard plate, a blade or blades between said plates, and an adjustable handle 120 comprising detachable ball and socket elements, said elements being enlarged and projecting laterally adjacent the ball and socket connection, thereby producing a limited adjustment.

125 16. In a safety razor, a comparatively short threaded section, a longer handle section adjustably and detachably connected to the short section, said sections being enlarged and projecting laterally adjacent 130

their connected ends to limit the adjustment thereof.

17. An adapter for a safety razor comprising a bar or plate, blade engaging means thereon, and means on said plate to prevent displacement of said adapter.

18. A safety razor comprising a front plate, ears formed integrally on said plate at opposite ends thereof, a longitudinally 10 extending slot or channel in said plate, an adapter, a blade, means carried by said adapter for engaging said blade, and a handle member for holding said parts in operative position.

19. In a safety razor, longitudinally channeled front plate, ears formed at the opposite ends of said plate, bearing surfaces at the opposite sides of said longitudinal channel, said bearing surfaces having a 20 plurality of slots or openings, a blade or blades, a flexible guard member, pins formed on said guard member adjacent its serrated sides, and a ball bearing handle for holding the parts in operative position.

20. In a safety razor, a flexible front plate, said plate having a central opening therein, lugs disposed between said opening and the ends of said plate, bearing surfaces formed at opposite sides of said front plate, pins on 30 said bearing surfaces at right angles thereto, a longitudinal slot in the outer surface of said front plate, notched out end sockets or bearings at opposite ends of said plate, an adapter having its ends formed at right angles to the base and a threaded stud midway between said ends, said adapter fitting

in said longitudinal channel and having its ends engaging the notched out end sockets, blades engaging the pins on the bearing surfaces on said front plate, a rigid guard plate, said plate having a plurality of openings in its central portion to engage with the studs on said front plate, and slots adjacent its sides to receive the pins adjacent the sides of said front plate, and a flexible handle, substantially as hereinbefore described.

21. An adapter for a safety razor comprising a bar or plate, ears or extensions formed at the opposite ends of said adapter, and means carried by said adapter for preventing longitudinal or angular displacement thereof.

22. In a safety razor, a front plate, a back or guard plate, a removable adapter, and means on one of said plates to retain the 5 adapter in position as to angular or longitudinal displacement.

23. A safety razor comprising a front plate, a longitudinally extending channel or slot therein, an adapter seated in said slot, 6 a cutting blade engaging said adapter, a resilient guard plate, and means for contracting and expanding said guard plate, substantially as described.

24. A safety razor comprising a front 6 plate, a longitudinally extending slot therein, and means detachably located within said slot having blade engaging means for adapting said razor for the utilization of different varieties of blades.

In testimony whereof I affix my signature.
WILLIAM A. BARRY.
